UNITED STATES PATENT OFFICE

GEORGE MORRISON, OF MERIDEN, CONNECTICUT, ASSIGNOR TO INTERNATIONAL SILVER COMPANY, OF MERIDEN, CONNECTICUT, A CORPORATION OF NEW JERSEY

DESIGN FOR A HOLDER FOR A CHILD'S SET COMPRISING KNIFE, FORK, AND SPOON

Application filed February 19, 1932. Serial No. 42,939. Term of patent 7 years.

To all whom it may concern:

Be it known that I, GEORGE MORRISON, a citizen of the United States, residing at Meriden, county of New Haven, and State of Connecticut, have invented a new, original, and ornamental Design for a Holder for a Child's Set Comprising Knife, Fork, and Spoon, of which the following is a specification, reference being had to the accompanying drawings, forming a part thereof.

Fig. 1 is a front elevation of the holder showing my new design;

Fig. 2 is a side view of the same; and

Fig. 3 is a top plan view thereof.

I claim:

The ornamental design for a holder for a child's set comprising knife, fork, and spoon, substantially as shown.

GEORGE MORRISON.
